UNITED STATES PATENT OFFICE

FREDERICK ARTHUR STEVENS, OF PROVIDENCE, RHODE ISLAND

DESIGN FOR A LENS STRAP

Application filed October 7, 1930. Serial No. 37,174. Term of patent 3½ years.

To all whom it may concern:

Be it known that I, FREDERICK ARTHUR STEVENS, a citizen of the United States, residing at Providence, in the county of Providence and State of Rhode Island, have invented a new, original, and ornamental Design for Lens Strap, of which the following is a specification, reference being had to the accompanying drawing, in which Fig. 1 is a front elevation of an ophthalmic mounting embody-

ing my new design; Fig. 2 is a plan of the same; and Figs. 3, 4 and 5 are sections taken upon the lines 3—3, 4—4 and 5—5, respectively, of Fig. 1, looking in the directions of the arrows.

I claim:

The ornamental design for a lens strap substantially as shown.

FREDERICK A. STEVENS.
